2 SHEETS SHEET 2.

UNITED STATES PATENT OFFICE.

JAMES MARION CALLAHAN, OF WASHINGTON, DISTRICT OF COLUMBIA.

ADJUSTABLE ARCH-SUPPORT FOR SHOES.

1,238,493.

Specification of Letters Patent. Patented Aug. 28, 1917.

Application filed August 9, 1916. Serial No. 113,846.

To all whom it may concern:

Be it known that I, JAMES M. CALLAHAN, a citizen of the United States, residing at Washington, in the District of Columbia, have invented a new and useful Adjustable Arch-Support for Shoes; and I do hereby declare the following to be a full, clear, and exact description of the invention, such as will enable others skilled in the art to which it appertains to make and use the same.

This invention relates to a new and useful adjustable arch support to be worn upon the interior of the shoe adjacent the arch, and the object of the invention is to provide a device of this kind for strengthening, reinforcing, and restoring fallen or broken or wrenched arches to their normal condition, whereby a person can walk without pain or inconvenience.

20 A further object of the invention is to provide a support, to reinforce and support the longitudinal and transverse arch of the foot.

A further object of the invention is to provide an insert pad between a plate and an insole, and which pad may be any suitable shape, and provided with an increased thickness at its forward end, to support the transverse arch, while the increased thickness of the pad near its central portion reinforces 30 and supports the longitudinal arch.

A further object of the invention is to provide a supporting plate constructed of two distinct thicknesses, in other words, a plurality of thicknesses.

35 A further object of the invention is to provide an insole, the heel portion of which is constructed of two thicknesses of leather, which may be secured together by any suitable means, preferably adhesive material or 40 stitches, to reinforce the heel of the insole relative to the metallic arch supporting plate.

A further object of the invention is to provide the extra thickness of leather for the 45 heel of the insole, as having a forwardly curved portion, to engage the correspondingly curved edge of the metallic arch reinforcing plate, thereby reinforcing the insole with relation to said plate, as well as providing abutment means to prevent the insole from creeping forwardly, and also reinforce-

ing the insole relative to where it bends adjacent said plate, as well as stiffening the heel of the insole.

A further object of the double thicknesses 55 of heel for the insole is to provide a more convenient and smoother cup for the heel.

A further object of the invention is to provide a pad having perforations, thereby ventilating, and at the same time lessening the 60 heat to the foot of the wearer.

A further object of the invention is to provide an arch supporting plate and an insole, which is attached to the plate at one end, and disconnected at the other end, whereby a 65 cushioning pad (for reinforcing and supporting the longitudinal and transverse arches) may be adjusted forwardly or rearwardly, as desired, until the wearer is entirely satisfied with the manner in which 70 the arch is supported.

A further object of the invention is to provide improved fasteners of any convenient shape, to fasten the cushioning pad to the 75 plate.

A further object of the invention is to construct the pad from one or a plurality of pieces, vulcanized or otherwise put or secured together.

80 A further object of the invention is to provide a resilient fastener to secure the pad to the plate, and when the pad has been adjusted to suit the wearer, the pad may be permanently fastened to the plate by riveting the fastener, which may be accomplished 85 by an ordinary shoe clerk with a pair of pliers or the like.

In practical fields, the details of construction may necessitate alterations falling within the scope of what is claimed.

90 The invention comprises further features and combination of parts, as hereinafter set forth, shown in the drawings, and claimed.

In the drawings:

Figure 1 is a view in perspective of the improved arch support arranged in the shoe, and illustrating the upper fiber insole piece as lifted, illustrating the pad in place.

Fig. 2 is a sectional view through the sole of the shoe, and through the arch support.

Fig. 3 is a cross sectional view on line 3—3 of Fig. 2.

Fig. 4 is an enlarged detail sectional view on line 4-4 of Fig. 1, showing the resilient fasteners.

Fig. 5 is a view in perspective of a tool or pair of pliers, used for riveting the resilient fastener, for permanently attaching the cushion pad, after the same has been adjusted as desired.

Fig. 6 is a view in perspective of a shoe, showing the arch support as applied, and the insole lifted, and the cushioning pad about to be inserted in place, illustrating modified fasteners.

Fig. 7 is a sectional view, showing the fasteners that are shown in Fig. 6.

Fig. 8 is a sectional view on line 8-8 of Fig. 7.

Fig. 9 is an enlarged sectional view showing the fasteners, which are disposed opposite to those shown in Figs. 6 and 7.

Fig. 10 is a detail perspective view of one of the fasteners shown in either Figs. 6 and 9.

Fig. 11 is a view of a portion of a shoe, illustrating the arch support in place, and the insole lifted, illustrating another form of cushioning pad, for instance, a shape resembling a shape of a pear.

Fig. 12 is a sectional view on line 12-12 of Fig. 11, showing the increased thickness of one end of the cushioning pad.

Fig. 13 is a bottom plan view of the heel part of the arch support, showing how the forward curved edge of the extra thickness of leather of the heel of the insole engages the curved edge recess at the rear of said plate.

Referring more especially to the drawings, 1 designates the arch portion of a portion of a shoe 2, and 3 denotes the lower-most reinforcing metal plate, which is designed to fit within the shoe, and to extend substantially the full length of the arch, and far enough forward to be free or clear of the joint of the big toe. This plate 3 tapers toward the edges, that is, in thickness, excepting at the rear, and at one side is provided with an upturned flange 4, which gradually curves upwardly, and gradually diminishes forwardly and rearwardly, as shown at 5 and 6. Said plate is provided with a plurality of openings 7, which may be arranged in a row, or in any other suitable manner. These openings are provided with counterbored portions 8 adjacent the undersurface of the plate. The rear edge of the plate is provided with curved recess 9, and the projections 10 near this recess are secured by rivets 11 to an insole 12, which is of a shape corresponding to the plate 3, and of sufficient length to overlie the forward edge of the plate 3. This insole where it overlies the forward edge of the plate 3 tapers in its thickness as shown at 13, so as to blend off into the inner surface of the shoe, and to afford a smooth surface for the foot. Secured to the under surface of the insole at its rear portion beyond the rear edge of the plate 3 is an additional piece of leather or other fiber 14. This piece 14 is secured by stitches 15 to the insole, and the forward portion of the piece 14 is provided with a curved projection 16 engaging the recess 9, thereby providing means to reinforce the insole adjacent where it bends beyond the rivets 11, which bending may occur when inserting the arch support in the shoe. The curved projection 16 engaging the recess 9 constitutes a joint, and the parts of this arch support may be so arranged in construction that this joint may occur on different locations. It can be readily seen that this joint may be made to occur very near where the shoe arch joins the heel, that is, nearer than shown in the drawings, and when this is the case, it will be seen that when the wearer of the shoe makes a step forward with one foot, the arch of the shoe of the other foot adjacent the heel tends to bend, owing to the upper of the shoe pulling upwardly and forwardly on the rear end of the heel, hence, there will be a bending of the insole adjacent said joint. Therefore, if this joint should be straight, that is, without the engaging projection and recess, there would be a decided bend on the insole, beyond the rivets 11, that is, toward the rear of the heel. However, by the provision of the curved projection 16 extending forwardly, slightly beyond the rivets 11 into the curved recess 9, the greater portion of this bend of the insole is reinforced, and by so reinforcing this bend of the insole, cracking, or breaking and the wear on the insole at this point incident to its constant bending, is considerably lessened, thereby, prolonging the life of the insole. Furthermore, a person's foot perspires, and, as is known, the perspiration is somewhat salty, having such a chemical action upon the leather or the material of the insole that the insole will crack considerably incident to the same becoming dampened from the perspiration alternating with the drying out. This cracking and breaking of the insole would be more decided if the joint consisting of the curved projection and the recess 9 were straight. Moreover, there occurs a bending of the insole, when inserting the arch support in the shoe; therefore, by means of this joint, the insole is reinforced where it bends. This additional piece 14 reinforces the insole when bending in either direction beyond the rear of the rivets 11. By means of the piece 14 the cup portion 17 of the insole, which cup receives the heel of the wearer, is reinforced, and the piece 14 acts to fill the space between the cup part of the insole and the heel of the shoe, to support the heel of the shoe.

the wearer. A cushioning pad 18, which may be constructed of a single or a plurality of pieces of any suitable cushioning material, preferably rubber or the like, is provided. This cushioning pad tapers in its thickness toward all of its edges, and is provided with an upcurved flange 19 at one side, which conforms to the flange 4 of the plate 3, and diminishes in thickness and converges rearwardly and forwardly into the edge of the cushioning pad, in conformity to the flange 4, in order to support the inside portion of the arch of the foot, while the pad near its central portion is so thickened as to reinforce and support the center of the arch of the foot, particularly the longitudinal arch. However, the forward part of the cushioning pad is thickened as shown at 20 in Fig. 11, so as to support the transverse arch of the foot. Referring to Figs. 1, 2, 3 and 4, it is to be seen that the flat disk ends 21 of the fasteners 22 are embedded in the cushioning pad in any suitable manner, or may be otherwise connected. The shanks 23 of the fasteners 22 are hollow, and their extremities are provided with bulged portions 24. The side portion of the bulge of the shank of each fastener and the side of the shank are provided with a plurality of longitudinal vertical slits 25, thereby providing a fastener, the shank of which is resilient. By means of these fasteners (two of which are to be carried by a cushioning pad) passing through any two of the openings 7 of the plate 3, the pad may be held in different adjusted positions, according to the desire of the wearer. In fastening the pad the bulged extremities of the shanks (which are yieldable or resilient) are forced through the openings 7, so that the bulged extremities will expand or spread partly into the counterbored parts 8 of said openings 7, thereby securing the pad in position. Should the wearer become accustomed and satisfied with the position of the cushioning pad, the pad may be attached permanently to the plate 3, by the employment of a pair of pliers or other tool in the hands of the ordinary shoe clerk, for riveting the fastener, as shown in Figs. 1 to 4, inclusive. The kind of pliers or other tool is shown in Fig. 5. It is to be observed that by means of the fasteners, the cushioning pad may be adjusted forwardly or rearwardly, as the case may be, preferably forwardly, when it is desired to reinforce or support the transverse arch of the foot, by means of the increased thickness 20 at the forward part of the cushioning pad. In Figs. 6 to 10, inclusive, the disk ends 26 of the fasteners 27 are also secured in the cushioning pad in any suitable manner, preferably by embedding them in the pad or vulcanizing the same. However, the shanks 28 of the fasteners 27 are solid, and

the shanks of those fasteners in Figs. 6 and 7 have their end portions 29 bent forwardly and rearwardly from each other. When attaching the cushioning pad having the fasteners 27, the pad is slightly pinched together, to allow the shanks 28 of said fasteners 27 to pass through the openings of the plate 3, whereby the extremities of said shanks may engage the counterbores of said openings of the plate 3. In Fig. 9 the end portions 30 of the shanks of the fasteners 27 are bent toward each other, as shown, instead of from each other; therefore, in this case it is necessary to stretch the pad to cause the shanks to enter said openings, thereby adjustably connecting the cushioning pad.

From the foregoing it is to be noted that an improved arch support has been devised, and one in which there are improvements, which are more simple and efficient in construction over the adjustable arch support set forth, illustrated, and claimed in the patent to J. M. Callahan, of June 13, 1916, Patent Number 1,187,255.

The invention having been set forth, what is claimed as new and useful is:—

1. In an arch support, the combination of an arch plate and an insole having its rear part a short distance from the rear edge of the insole connected to the plate and its forward end free and disconnected, of a cushioning pad interposed between the insole and the plate and having fastening connections with the plate, and an additional heel piece secured to the under face of the heel of the insole, the rear edge of said plate and the forward edge of the heel piece having interengaging recess and projection connections to reinforce the insole where it may bend beyond the rear of the plate.

2. In an arch support, the combination of an arch plate and an insole having its rear part a short distance from the rear edge of the insole connected to the plate and its forward end free and disconnected, of a cushioning pad interposed between the insole and the plate and having fastening connections with the plate, and an additional heel piece secured to the under face of the heel of the insole, the rear edge portion of the plate being abrupt and having a curved recess, the forward edge of the heel piece being abrupt and engaging the abrupt edge at the rear of the plate, and provided with a curved projection to engage the curved recess, thereby reinforcing the insole incident to its bending beyond the edge of the plate.

3. In an arch support, an arch plate having its rear edge provided with a curved recess, an insole connected to the plate and having its forward and rear parts free and disconnected from the plate, a cushioning pad between the forward part of the insole

and the plate, and a heel piece secured to the under face of the heel of the insole and having its forward edge provided with a curved projection to engage said curved recess, thereby reinforcing the insole incident to its bending beyond the edge of the plate.

In testimony whereof I have signed my

name to this specification in the presence of two subscribing witnesses.
